[57] CLAIM

The ornamental design for a safety headguard, as shown and described.

DESCRIPTION

FIG. 1 is a perspective view of a safety headguard showing my new design;

FIG. 2 is a side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a side elevational view of a second embodiment thereof, the only difference being the addition of two straps on the rear portion of the headguard; and,

FIG. 8 is a rear elevational view thereof.

The person shown in broken lines in FIG. 1 is shown for illustrative purposes only and forms no part of the claimed design.
